TWIN BED AND LOUNGE

Truman S. Ziegenfuss, Los Angeles, Calif.

Application August 1, 1947, Serial No. 765,309

9 Claims. (Cl. 5—2)

1

My invention relates generally to beds, couches, and lounges, and more particularly to a piece of furniture of the class stated which is adapted to be used either as a dual lounge; or which may be quickly and easily converted to a double bed.

While structures constructed to accomplish the above purpose have been designed in the past, they have not been entirely successful for several reasons.

First, it is generally necessary to sacrifice one or the other of the two functions in order to make the device convertible from one function to the other. Thus, for example, many so-called "studio couches" while providing an adequate and attractive appearing couch for daytime use, are not comfortable when converted into a bed for sleeping purposes. On the other hand, when adequate springs and mattresses are built into such a device to provide sleeping comfort, it is often necessary to make the structure large and somewhat cumbersome when it is converted to a lounge or couch.

Furthermore, such convertible studio couches have usually been complicated in mechanism and difficult to operate, requiring lifting of the structure, and often removal of some of the parts thereof. Such complications in structure make for difficulties in operation, particularly by housewives, and add considerably to the cost of manufacture.

Bearing in mind the above difficulties encountered in previous structures of the class described, it is a major object of my invention to provide a twin lounge or couch structure which may be easily and quickly adapted to any one of three different uses, namely:

A lounge for daytime use;

A pair of twin beds for sleeping purposes; or,

A double bed.

Another object of my invention is to provide an article of furniture of the class described which is particularly adapted and designed to conserve space and thus is suitable for use in small apartments and similar dwellings having limited floor space.

Still another object of my invention is to provide a combination lounge and twin bed structure which is unique in its appearance and operation, and which in one of its forms, is adapted to be placed in the corner of a room.

A further object of my invention is to provide a structure of the class described which may be efficiently used with a single end table unit accessible to both of the twin units.

2

The foregoing and other objects and advantages of my invention will become apparent from the following detailed description of two forms, the description being considered in connection with the attached drawings in which:

Figure 1 is a perspective view of one form of my invention shown in open position, such as for daytime use;

Figure 2 is a perspective view of the device of Figure 1 shown in closed position preparatory to making up a double bed;

Figure 3 is a plan view of the device of Figure 1;

Figure 4 is a partial elevational section taken on the line 4—4 in Figure 3;

Figure 5 is an enlarged elevational view of a portion of the device shown in Figure 2;

Figure 6 is an enlarged elevational section taken on the line 6—6 in Figure 3;

Figure 7 is an elevational sectional view taken on the line 7—7 in Figure 2; and,

Figure 8 is a perspective view of an alternate form of my invention.

With reference first to the form illustrated in Figures 1 through 6, the reference character 10 designates a twin bed unit of more or less conventional internal structure differing, however, from conventional design in its exterior configuration. This difference in configuration lies principally in the fact that the head end of the bed is formed as a semi-circular arc 11 having a diameter substantially equal to the width of the bed unit 10.

Still referring to the form illustrated in Figure 1, it will be noted that the two semi-circular ends 11 of a pair of bed units 10 are received in arcuate socket-like depressions or concavities 12 of an end table unit 50. The end table unit 50 may be of various types of construction, and may if desired, be provided with upholstered surfaces 55 forming heads adjacent the head ends 11 of the bed units 10. In the present instance, the table 50 is enclosed and of generally right triangular transverse cross section. The sides 51 and 52 being at right angles, are adapted to be received in the corners of a room with the concavities 12 in the hypotenuse side 53 facing outwardly.

A transverse lower shelf-like member 56 is secured to the sides 51 and 52 and the table is supported above the floor by three short legs 57. Additionally, a book shelf 58 may be provided which is accessible to persons sitting or lying on either of the bed units 10, whether these be in

the open position illustrated in Figure 1, or in the closed position shown in Figure 2.

In order that the bed units 10 are held into the depressions 12 at all times, a horizontal U-shaped bracket 15 is secured to an under surface of the lower shelf 56 of the table unit 50 and carries a pair of pivot pins 16 welded or otherwise suitably secured in the extended corners thereof, the nature of the pivot pin and its attachment to the bracket 15 being best seen in Figure 6. A suitable rubber cap 17 or other protective means is secured to the bottom of each of the pivot pins 16 in order that these members may rest on the floor without marring the same.

Each of the bed units 10 is provided with a pivot receiving socket 18 which is secured to the under surface of the bed 10 at approximately the center of curvature of the arcuate head end 11. This socket is secured to the bed by means of a plurality of wood screws 19 which are secured in a transverse member 20, which in turn is secured to the bed structure as illustrated in Figure 7.

The bed unit 10 itself, comprises a lower box frame 21 in which is carried a flat bottomed member 22 of plywood or other similar material, on which rest the conventional coil bed springs 23 which support padding 24. The entire spring portion of the bed 10 is covered by suitable ticking or other covering material 25. A mattress 26 of usual construction except for a conforming semi-circular end, is placed above the spring portion 27.

The frame 21 is supported on four relatively short legs 30 which in turn are provided with casters of conventional design, such for example as the single ball type caster 31 illustrated in Figure 5. The two inner legs at the foot end of the bed units 10 are provided with fastening means, such for example, as the hook 32 and pin 33 illustrated in Figure 5. Thus when the beds are swung into the closed position as illustrated in Figure 2, the fastening means may be used to hold them in said position against accidental separation.

Thus it will be seen that the twin bed structure illustrated in Figure 1 may be quickly and easily swung to the open position shown in Figure 1, or alternately, closed to the position in Figure 2 and locked in the latter position by the fastening means 32-33. When locked together in the position illustrated in Figure 2, the two bed units may be made up either as separate twin beds, or may be made up as a double bed.

By reference to Figure 3 it will be noted that the space occupied by the two bed units 10 when placed in a corner is considerably less than that which would be required for two twin beds of conventional design, and an end table. This conservation of space is effected by the arcuate ends 11 which may nest together into the concavities 12 in the end table 50, thus saving a considerable amount of floor space, while not detracting from the usefulness or appearance of the device.

A small triangular filler member 35 is placed in the interstice formed between the curved ends 11 and the end table 50. This filler member 35 may be either constructed as a separate piece in the form of a hassock or may be constructed as a projection of the table 50.

A wall bed structure 45 illustrated in Figure 8, while similar in operation and in other respects to the structure illustrated in Figure 1, differs somewhat in that it is adapted to be placed

against a straight wall rather than in a corner. The same bed units 10 are employed in the wall bed 45 as are used in the previous embodiment. The end table 40 used in the wall bed 45 is somewhat larger than that used in the previous embodiment and provides separate book shelves and cupboards 41 and 42 respectively for each of the bed units 10. Furthermore, a somewhat larger filler member 43 is required for the structure of Figure 8.

The operation of the wall bed 45 is substantially the same as that of the form shown in Figure 1, except that the angle to which the bed units 10 will open is somewhat less than that in the previous embodiment.

The pivot members 16 provided in the form illustrated in Figure 1 are also used in the form shown in Figure 8 and are supported by a bracket 15 from a lower shelf in the end table unit 40.

Thus it will be seen that I have provided a simple and attractive piece of furniture which may be quickly and easily converted from a twin lounge to a double bed, or may, if desired, be used as a pair of twin beds. In the form illustrated in Figure 1 the location of the end table 50 is such that it may serve to support a reading lamp which will furnish light for occupants of either of the bed units 10.

Since legs 30 are provided both at the head and foot ends of the bed units 10 they may be readily detached from either end table unit 50 or 45 merely by lifting the head end to disengage the socket 18 from the pivot pin 16. Furthermore, as shown in Figure 4, the bracket 15 is removably secured to the table 50 by wing nuts 58 whereby it may be demounted for shipping purposes.

In some instances the bracket 15 and the pivot 16 may be dispensed with since the cradling action of the concavities 12 which receive the arcuate ends 11 is such as to hold the arcuate end of each bed 10 in proper position as it is being pivoted. This mode of operation is particularly practical when the filler member 35a is constructed as a portion of the table itself as illustrated in Figure 4.

While the furniture pieces shown and described herein are fully capable of achieving the objects and providing the advantages hereinbefore stated, they are capable of considerable modification within the spirit of the invention. Therefore I do not mean to be limited to the forms shown and described herein but rather to the scope of the appended claims.

55 I claim:

1. In an article of furniture of the class described: a table having a pair of vertical cylindrical concavities formed in a side thereof; means secured to said table adjacent a lower surface thereof, projecting beyond said table, and having a pair of vertical pivots formed therein, one positioned substantially at the center of curvature of each of said concavities; and a pair of bed units each rotatably engaged with one of said pivots for horizontal swinging motion thereabout.

2. In an article of furniture of the class described: a generally triangular table having two substantially equal sides substantially at right angles to one another and a third side forming a hypotenuse therewith, said third side having a pair of laterally spaced concavities therein; means secured to said table adjacent a lower surface thereof, projecting beyond said hypotenuse side, and having a pair of vertical pivots formed therein, one positioned substantially at the cen-

ter of curvature of each of said concavities; and a pair of bed units each rotatably engaged with one of said pivots for horizontal swinging motion thereabout.

3. In an article of furniture of the class described: a generally triangular table having two substantially equal sides substantially at right angles to one another, a third side forming a hypotenuse therewith, and a horizontal shelf secured to said sides adjacent the lower ends thereof of said third side having a pair of laterally spaced concavities therein; means secured to said shelf projecting beyond said hypotenuse side, and having a pair of vertical pivots formed therein, one positioned substantially at the center of curvature of each of said concavities; and a pair of bed units each rotatably engaged with one of said pivots for horizontal swinging motion thereabout.

4. In an article of furniture of the class described: a table unit having a pair of parallel arcuate concavities in a vertical side thereof; a pair of bed units each having an arcuate convex end received in one of said concavities; and means fixed to said table unit and pivotally connected to each of said bed units at points substantially on the axis of curvature of said ends whereby to adapt said bed units for swinging motion about said axes.

5. In an article of furniture of the class described: a table of generally right triangular transverse cross section having a pair of cylindrical concavities in a hypotenuse side thereof and a transverse shelf; a bracket secured to said shelf and projecting beyond said hypotenuse side; a pair of pivot members secured to said bracket, each substantially on the axis of one of said concavities; a pair of bed units each having a convex end complementary to, and received in one of said concavities; and pivot means secured to each of said beds adjacent the center of curvature of said ends and engaged with one of said pivot members whereby to permit horizontal swinging motion of said bed units about said centers.

6. In an article of furniture of the class described: a table unit having a pair of arcuate concavities in a vertical side thereof; and a pair of bed units each having an arcuate convex end pivotally secured in one of said concavities whereby to adapt said bed units for swinging motion about the centers of curvature of said arcuate concavities.

7. In an article of furniture of the class described: a generally triangular table having two substantially equal sides substantially at right angles to one another, a third side forming a hypotenuse therewith and a pair of arcuate concavities formed in said hypotenuse side; and a pair of

bed units, each having an end pivotally secured in one of said concavities for horizontal swinging motion of said beds about the centers of curvature of said concavities.

- 5 8. An article of furniture comprising a self supporting table having a top provided with two adjacent edges extending at an angle to each other to fit in the corner of a room and having other edges facing outwardly away from the corner of the room, a pair of similar beds each positioned with an end thereof adjacent and at a lower lever than said outwardly facing edges of said table top, and means pivotally securing the adjacent ends of said beds to said table with corresponding portions of the ends of said beds being positioned at equal distances from the apex of the angle formed by said two adjacent edges of said table top, said beds being arranged for independent horizontal pivotal movement from positions in which one bed extends from said table along and against each adjacent wall of the room to positions in which the beds extend outwardly from the table in parallel side by side relationship.
- 10 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540
9. An article of furniture comprising a self supporting table of a configuration to fit in the corner of a room formed by two angularly disposed walls of the room, a member secured to and fixed relative to said table and having a pair of horizontally spaced pivot points, a first bed pivotally connected to said member at one of said pivot points for horizontal pivotal movement, and a second bed pivotally connected to said member at the second of said pivot points for independent horizontal pivotal movement of said beds from positions in which one bed extends from said table along each adjacent wall of the room to positions in which the beds extend outwardly from the table in parallel side by side relationship.

Certificate of Correction

January 24, 1950

Patent No. 2,495,494

TRUMAN S. ZIEGENFUSS

It is hereby certified that error appears in the printed specification of the above numbered patent requiring correction as follows:

Column 6, line 12, for the word "lever" read *level*;
and that the said Letters Patent should be read with this correction therein that the same may conform to the record of the case in the Patent Office.

Signed and sealed this 23rd day of May, A. D. 1950.
